UNITED STATES PATENT OFFICE.

WILLIAM EARL PARENT, OF PHILADELPHIA, PENNSYLVANIA, ASSIGNOR, BY MESNE ASSIGNMENTS, TO THE YALE & TOWNE MANUFACTURING COMPANY, OF STAMFORD, CONNECTICUT, A CORPORATION OF CONNECTICUT.

LOCK.

Application filed May 25, 1922. Serial No. 563,637.

To all whom it may concern:

Be it known that I, WILLIAM E. PARENT, a citizen of the United States, residing in Philadelphia, Pennsylvania, have invented 5 certain improvements in Locks, of which the following is a specification.

The object of my invention is to provide a lock especially adapted for use on cupboards and lockers, the combination which 10 can be changed without removing the lock from the door to which it is attached.

In many instances, the key of a locker is lost and it is desirable to change the combination without removing the lock from the 15 door. This is accomplished in my invention by inserting a special key in an opening at the back of the lock and moving an element, which will change the combination so that it can only be operated by the insertion of 20 a particular key.

In the accompanying drawings:

Fig. 1 is a view of a lock made in accordance with my invention with the cap plate removed;

25 Fig. 2 is a sectional view on the line 2—2, Fig. 1;

Fig. 3 is a view showing a portion of the lock with some of the parts removed;

Fig. 4 is a rear view of the lock casing; 30 Fig. 5 is a perspective view of the bolt;

Fig. 6 is a detached perspective view of the shifter;

Fig. 7 is a perspective view of the pawl which engages the shifter;

35 Fig. 8 is a perspective view of the stump; Fig. 9 is a perspective view of a tumbler carried by the bolt;

Fig. 10 is a perspective view of one of the series of tumblers mounted on the 40 casing;

Fig. 11 is a perspective view of the key post;

Fig. 12 is a perspective view of a key;

45 Fig. 13 is a perspective view of the stump key; and

Fig. 14 is a view of a modification.

Referring to the drawings, 1 is the casing of the lock having extensions 2 by which it is secured to the cupboard, or locker. 3 50 is the cap plate, which is secured to the casing by screw bolts 4. 5 is a cylindrical extension on the cap plate in which the key post 6 is located. This key post has a slotted head 7, which fits back of a flange on the

extension 5 and has, at the opposite end, an 55 arm 8, which engages the bolt 9. On the first movement of the key post, the arm travels over the surface 10 of the bolt, projecting the bolt beyond the casing, as in Fig. 1. On continuing this movement, this arm 60 will strike the portion 11 of the bolt and will retract it.

On the bolt 9 is a stump 12 and pivoted to a post 14 on the casing is a series of tumblers 13, which are slotted so that, when 65 the key moves these tumblers in order that their slots will be in line with the stump 12, the bolt can be retracted.

Pivoted to the post 15 on the bolt 9 is a tumbler 16, formed as shown in Fig. 9, and 70 having a slot 17. This tumbler can be moved so that its slot will be brought in line with a stump 18 on a sliding plate 19, Fig. 8. The key must be so cut that when the key post is turned, the slots in the 75 tumblers 13 and the slot in the tumbler 16 are brought in line with their respective stumps, after which the bolt can be withdrawn by the arm 8 of the key post striking the portion 11 of the bolt.

80 Mounted in the casing 1 is a key post 20 to which is secured a shifter 21, Fig. 6. On the shifter is an arm 22 having a pin 23, which enters a slot 24 formed by two projections extending from the stump plate 19 85 so that, when the key post 20 is turned by the setting key, Fig. 13, the plate 19 and its stump 8, can be raised and lowered in order to alter its position in respect to the bolt and its tumbler 16.

90 The shifter 21 has a segmental extension 34 having teeth 25, which are engaged by a pawl 26, Fig. 7, pivoted to a post 27 on the casing. This pawl is so formed that it will allow the shifter to be moved, but will hold the shifter in any position in which it is adjusted.

95 The stump, in the present instance, is held by a spring 28 against the wall of the lock casing, the spring being mounted on a post 29 and the end of the spring extending through a hole 30 in the stump 18. The tumblers and the pawl are provided with the usual springs, as shown in Figs. 7, 9 and 10.

100 In Fig. 14, a modification of the invention is illustrated in which the stump 18^a is mounted on a slotted plate 19^a. A pin 31 on

the casing extends through this slot. The stump plate has a spring 28^a. On the casing is a fixed rack 32 having beveled teeth engaged by a tooth 33 on the stump plate. 5 20^a is a key post having a toothed arm 36, which is arranged to enter one of a series of notches 35 in the plate 19^a.

By this construction, the main key is inserted in the lock and the bolt tumbler 16^a 10 is operated and brought into alignment with the stump 18^a and the bolt retracted so that the stump 18^a will enter the slot 17^a in the tumbler. Then the post 20^a is turned by its 15 special key so as to withdraw the toothed arm. This leaves the plate 19^a free to slide. By inserting another key in the lock, while the bolt is withdrawn, the tumbler 16^a moves the plate 19^a through its stump to a new 20 position. The key post 20^a is moved so that its arm 36 will again engage the plate and lock it in its new position.

I claim:

1. The combination in a lock, of a casing; a key post at the face of the lock; a bolt; 25 means for engaging the bolt; a slotted tumbler pivoted to the bolt; a sliding stump mounted in the casing and arranged to be moved into alignment with the slot in the tumbler; a pawl for locking the stump in 30 the position in which it is adjusted; and a key post at the back of the lock to receive a key for actuating the stump mechanism.

2. The combination in a lock, of a casing; a bolt mounted in the casing; a tumbler pivotally mounted on the bolt and having a 35 slot; a plate slidably mounted on the casing and having a stump arranged to enter the slot in the tumbler when the bolt is retracted; a spring engaging the plate; a pivoted shifter mounted on the casing and having a 40 key post; an arm on the shifter pivotally connected to the stump plate; a segmental extension on the shifter having a series of teeth; a pawl pivotally mounted on the casing and arranged to engage the teeth of the 45 shifter; a stump on the bolt; a series of tumblers pivoted to the casing and slotted for the reception of the stump; and a key post arranged to receive a key so that, on turning the key, the several tumblers will 50 align with their stumps and the bolt will be retracted.

3. The combination in a lock, of a casing; a bolt mounted in the casing; a slotted tumbler pivotally mounted on the bolt; a plate 55 having a stump projecting therefrom; a shifter pivotally mounted on the casing; a key post at the center of the shifter by which the shifter is adjusted, said shifter having an arm engaging the stump plate; and a ratchet mechanism for locking the shifter in the position in which it is adjusted.

WILLIAM EARL PARENT.
